TOY VILLAGE

Ralph W. Crawford and Paul D. Snyder, East Aurora,
N.Y., assignors to The Quaker Oats Company, Chi-
cago, Ill.

Filed Dec. 18, 1973, Ser. No. 425,706

Term of patent 14 years

Int. Cl. D21—01

U.S. Cl. D34—15 LL

FIG. 3

FIG. 4

FIG. 5

FIG. 1 is a front perspective view of a toy village showing our new design;

FIG. 2 is a top plan view thereof;

FIG. 3 is a rear elevational view as seen along the line 3—3 in FIG. 2;

FIG. 4 is a rear elevational view as seen along the line 4—4 in FIG. 2; and

FIG. 5 is a rear elevational view as seen along the line 5—5 in FIG. 2.

We claim:

The ornamental design for a toy village, substantially as shown and described.
